UNITED STATES PATENT OFFICE.

EVERETT H. BROWN, OF PHILADELPHIA, PENNSYLVANIA, ASSIGNOR TO
LEICESTER AND CONTINENTAL MILLS COMPANY, OF GERMANTOWN,
PHILADELPHIA, PENNSYLVANIA, A CORPORATION OF NEW JERSEY.

DESIGN FOR A KNIT FABRIC.

No. 38,214.

Specification for Design.

Patented Aug. 28, 1906.

Application filed July 18, 1906. Serial No. 326,795. Term of patent 7 years.

To all whom it may concern:

Be it known that I, EVERETT H. BROWN, a citizen of the United States, residing in the city of Philadelphia, State of Pennsylvania, have invented a certain new, original, and ornamental Design for a Knit Fabric, of which the following is a specification, reference being had to the accompanying drawing, forming a part hereof.

My design is applicable to and intended for the surface ornamentation of that class of

knit fabrics commonly called "eider-down" fabrics, and the said drawing is a plan view thereof.

I claim—

The ornamental design for a knit fabric, as shown.

EVERETT H. BROWN.
